DEVICE FOR SHORING OR SPRAGGING

Walter Sylvester, Tunstall, England

Application August 14, 1939, Serial No. 239,953
In Great Britain August 15, 1938

7 Claims. (Cl. 248—354)

This invention relates to a device for shoring or spragging, for use for example in mines.

The object of the invention is an improved device adapted to be attached to a pit prop or other form of roof support that may be available or for use on its own.

According to the invention the improved device comprises a post having at least one step, adapted to receive the butt of a sprag.

In a preferred embodiment of the invention the post is provided with means for securing it to a pit prop and is of channel section. The steps to receive the butt of the sprag may be fixed or it may consist of an adjustable step adapted to be engaged with fixed steps on the post.

In the accompanying drawing—

Fig. 1 is a front elevation of one example of a device made in accordance with the invention; Fig. 2 is a section on line 2—2 of Fig. 1.

Fig. 3 is a plan of Fig. 1.

Fig. 4 is a side elevation of Fig. 1.

Fig. 5 is a side elevation of a modified form of the invention.

Fig. 6 is a plan of Fig. 5.

As illustrated in Figs. 1 to 4 the improved device comprises a post 1 of channel section adapted to be placed against the flange of an H section prop 2 (see Fig. 3) and having at its upper and lower ends means for fixing it securely to the prop. The means at the lower end of the post comprises a pair of side plates 3, welded to the post and adapted to engage the edges of the flange of the prop so as to locate the post against lateral displacement. At the upper end the fixing means comprises at one side a fixed claw 4 adapted to be hooked over the flange of the prop and at the other side a lever 5, one part of which is adapted to be engaged behind the other flange (see Fig. 3) and the other part of which acts both as a handle and as a weight to hold the lever in such engaged position (see Fig. 1). The lever 5 is pivoted in a bracket 5a welded to the side of the post. The engaging lever has a bevel 6 giving a wedging action to grip the flange securely.

At its lower end the flanges of the channel are turned inwardly at 7 and such lower part may be filled with wood 8. The object of this construction is to give greater security and to protect the post against undue damage as it may be subjected to rough use by impact of the coal cutter or other apparatus.

Above such lower part a series of fixed steps 9 are welded between the flanges, each step hav-

ing a lip 10 at its outer end and being welded to the sides and to the bottom of the channel. The outer end of each step is supported by a riser 11 welded thereto and also similarly welded 5 in the channel. For additional stiffness, such riser may be of arched shape with legs 12 and a cross piece 13 as shown for the uppermost riser in Figs. 1 and 4. In the process of welding, particular attention will be directed to building up a secure support on the riser which will be required to support the weight on the sprag. The step and riser could be formed as a single L shaped member which could be fitted with its angle welded to the back of the channel and fitted so that the upper part forms a strut below the outer edge of the step above it.

In use the post is easily and quickly secured to the roof prop by hooking its claw 4 on to the flange thereof bringing the side plates 3 into position embracing the flange and then operating the lever 5 to lift it and then lower it behind the flange of the prop. The sprag may then be fitted in known manner, using any of the several steps, whichever may be the most convenient. The post itself rests on the floor and may have a foot of its own of any suitable type and construction.

In a modification of the invention as shown in Figs. 5 and 6 the post 14 still of channel section 30 is formed with outwardly turned flanges 15 at its upper part. Welded to the bottom of the channel at its upper part are a number of smaller step pieces 16 whilst a sliding step 17 for the butt of the sprag is provided, having at its upper end hooks or lugs 18 to engage behind the flanges of the post. At its lower end, such sliding step has a toe 19 adapted to be engaged with the step pieces 16 at the back of the channel. The upper end of the sliding step is formed 40 as a socket 20 to receive the butt 21 of a sprag. The side flanges 15 will be inwardly turned at their lower ends as shown in Figs. 1 to 4. The step pieces 16 are not the full width of the channel and at the upper end of the sliding step is 45 fixed a bridge piece 22, the ends of which engage the back of the channel and can pass the ends of the step pieces 16.

In an alternative construction the side flanges 15 are inwardly turned for their full length and the sliding step modified accordingly.

The modified form of the device is otherwise constructed in the same way as the first described example for its attachment to a pit prop.

In use when the post has been secured to the prop the adjustable step is set in the required

position and the sprag is then fitted in known manner. The adjustable step is preferably shaped to form a socket for the butt of the sprag.

The bridge piece 22 at the upper part of the slideable step provides support against the bottom of the channel, on each side of the step pieces, so as to take any inward thrust on the bottom of the channel and not on the bent flange.

Obviously, either form of the device could be adapted for fixing to pit props of other than H section steel props, the back of the device being suitably shaped flat or round and for wood props they may have claws to penetrate the wood to prevent their displacement. The device may alternatively be fixed to the prop by chain or other suitable means. Also the device could be placed against a back wall and suitably located therein and used to fix a sprag where there is no convenient pit prop or other roof support structure to which it could be attached.

What I claim is:

1. A device for shoring or spragging in mines comprising a channel-shaped post having a plurality of fixed steps arranged in the channel and each adapted to receive the butt of a sprag.

2. A device for shoring or spragging in mines comprising a channel-shaped post having a plurality of inclined fixed steps arranged in the channel and projecting beyond the sides of the same and each provided at its outer edge with a lip so that the steps are adapted to receive and locate the butt of a sprag.

3. A device for shoring or spragging in mines comprising a channel-shaped post having a plurality of inclined fixed steps arranged in the

channel and projecting beyond the sides of the same and each provided at its outer edge with a lip so that the steps are adapted to receive and locate the butt of a sprag, the steps being provided at the upper part of the post whilst the sides of the channel at the lower part are inwardly turned.

4. A device for shoring or spragging in mines according to claim 3 wherein a wooden filling is provided in the lower part of the post between the inturned flanges.

5. A device for shoring or spragging in mines comprising a post having at least one step adapted to receive the butt of a sprag and having means for securing it to a pit prop, said means comprising positioning means at the lower end of the post and clamping means at the upper end of the post, the clamping means comprising a fixed claw on one side adapted to engage behind the flange of a girder prop and a pivoted claw at the other side adapted to be moved behind the flange, the two claws forming a clamping to embrace the flange between them.

6. A device for shoring or spragging in mines comprising a channel-shaped post having a plurality of fixed steps arranged in the channel and a step adapted to receive the butt of a sprag, slidably mounted on the channel and having a toe adapted to be engaged with any one of the fixed steps.

7. A device according to claim 6 wherein the sides of the channel are outwardly flanged and wherein the sliding step is mounted on such flanges.

WALTER SYLVESTER.
